(57) **CLAIM**

The ornamental design for a closure for an electrical cord, as shown and described.

DESCRIPTION

FIG. 1 is an exploded perspective view of a closure for an electrical cord showing my new design, the broken-line disclosure in the views being for illustrative purposes only and forming no part of the claimed design; opposed sides of an electrical cord shown in phantom;

FIG. 2 is a front isometric view of my new design for the closure;

FIG. 3 is a rear isometric view of my new design for the closure;

FIG. 4 is a front view thereof;

FIG. 5 is a rear view thereof;

FIG. 6 is a top view thereof;

FIG. 7 is a bottom view thereof;

FIG. 8 is a left side view thereof; and,

FIG. 9 is a right side view thereof.
